UNITED STATES PATENT OFFICE.

LEVI HETFIELD, OF PLAINFIELD, NEW JERSEY.

COAL POCKET AND DUMP.

SPECIFICATION forming part of Letters Patent No. 268,671, dated December 5, 1882.

Application filed September 6, 1882. (No model.)

To all whom it may concern:

Be it known that I, LEVI HETFIELD, of Plainfield, Union county, New Jersey, have invented a new and useful Improvement in Coal Pockets and Dumps; and I do hereby declare that the following is a full and exact description thereof, reference being had to the accompanying drawings, and to the letters of reference marked thereon, making a part of this specification.

My invention relates to the construction of dumps for unloading and storing coal from railroad-cars.

Its object is to so facilitate the loading of carts or wagons from the dump and the unloading of cars upon the dump as that the loading and the unloading may be performed simultaneously and at all times without detaining either the wagons or the cars, and, furthermore, to economize space in the handling and in the storing of large quantities of coal to be delivered from railway-cars and loaded into carts or wagons.

It consists in an improved construction of trestles, pockets, and dumps, as is hereinafter fully explained.

In the accompanying drawings, Figure 1 is a vertical section through my improved trestle and coal-dump, and Fig. 2 a side elevation thereof.

A A represent the uprights, B the cross-bars, and C the longitudinal beams, of the trestle-work upon which the railway is carried by which the cars are brought to the dump. D 35 D are the rails laid and secured thereon in the usual manner. The uprights are secured to transverse sills E E, and converge to the cross-beams at the top in the usual manner.

At the base of each of the uprights in the 40 trestle A A B stout timbers F F are secured to the sill E, to extend upward and outwardly at an angle with said uprights more or less acute, as shown in Fig. 1, and are strongly secured in position by transverse joists G G, 45 bolted to the sides of the uprights and of said side timbers to extend inwardly from the opposite sides of the trestle until they meet centrally and at such a height and such an angle as that their upper edges intersect at a central 50 point on the under side of the upper cross-

beams, B, of the trestle, (seen at H, Fig. 1.) The upper ends of the side timbers, F, are also stayed and tied to the cross-ties J J upon the longitudinal track-beams C C by means of tie-beams K.

Longitudinal beams L' L' are inserted between the inclined joists G G to support a flooring, L L, laid thereon to form the bottom of the pockets M of my improved dump. The ends of the longitudinal floor-beams are tenoned into the inclined joists, and otherwise stoutly braced and secured thereto.

Planking N N, secured against the inner face of the inclined side timbers, F F, above the flooring L', serves to close in the outer side of 65 the pockets, which are strengthened by truss-rods P P, extended diagonally from transverse strips R R, laid under the floor-beams, to strips R' R'' upon the outer sides of the pockets, and also from said strips R' R'' to the cross-ties on 70 the track-beams C C, all as clearly shown in Fig. 1.

One or more openings, S, are formed in the crest or ridge formed by the flooring of the pockets M on either side at their line of intersection under the center of the track, these 75 openings being of suitable size to admit of a free delivery thereinto of the coal as it is dropped from the bottom of the cars run upon the track over the same. Immediately under 80 said openings a supporting-plate, T, is suspended and upheld by means of suspension-rods U U.

The upper surface of the plate T may be beveled or inclined from the center to each 85 side, as shown in the drawings. The opening left between the plate T and the flooring L' of the pocket is boxed in and closed at the ends and sides by suitable planking, but longitudinal side apertures are left therein, which are 90 opened or closed at pleasure by means of gates V V, operated from the level of the track above by means of rods W, incased and playing freely in iron tubes W', which serve to prevent the rods from being confined by a pressure of coal 95 against them. These gates and rods are preferably inclined, as shown in Fig. 1 of the drawings, to facilitate their movement. When the gates are opened the coal which may drop from the cars above into the space over the sup- 100

porting-plate T is allowed to fall into the large storage-space formed under the pockets M, between the uprights of the trestle. The pockets M are so braced and strengthened by the rods 5 P P as to need no central supports between the trestle-beams other than double posts Y Y, placed under the outer edge of the pockets midway of their length, so that the entire space under the trestle and its pockets is left free 10 and unobstructed for the reception and storage of the coal. The coal thus stored is retained in place by removable planking Z Z, fitted against upright posts a a, which are secured at the bottom to the ends of the sills E E, and at the 15 top to the outer bottom edge of the pockets, as shown in Fig. 1.

The gates V V are readily raised, when required, by means of a bar, e, inserted through a ring on the upper end of each gate-rod W and 20 into a fixed ring or socket, b, secured for the purpose upon one of the cross-ties. A single detachable rod or lever may thus be employed to move any and all of the gates.

The height of the trestle of A B E and the 25 inclination of the flooring of its pockets M M is so adjusted as to permit a cart or wagon to be readily driven under the lower edge of the pockets either to be loaded directly therefrom or from the coal stored beneath.

30 In order to load the wagons or carts directly from the pockets one or more central openings, f, are formed at the level of the flooring of each pocket, in the outer side thereof, so that the flooring-planks may be extended out through 35 said opening in an unbroken plane or incline to form an outward chute for the coal. The sides and top of the chute so formed are properly inclosed to prevent the coal descending through the same from scattering, and a screen, 40 g, is fitted in the bottom thereof, over which the coal must slide before being delivered from the end of the chute into the cart or wagon waiting in position to receive it. The delivery of coal from the pocket into and through each 45 chute is controlled by a suitable gate, h, operated by a long lever, i, hinged at its inner end to the side of the pocket, and which is also connected to the top of the gate by a hinge, as shown in Fig. 1. The gate-levers i i are 50 of such length as that the driver of the wagon to be loaded may, when standing therein, operate the same. With double gates, as illustrated in Fig. 2, the driver, standing in position between them, may open both simultaneously.

55 The coal, passing rapidly down each chute, is thoroughly screened in its descent, and the wagon may thus be filled in a few moments with coal ready screened and freed from dust and dirt, without any manual labor other than 60 as required for opening and closing the gates.

Upon the arrival of a car-load of coal upon the dump it may be emptied immediately into the pockets M M ready for automatic delivery into the wagons, the gates V V being kept 65 closed. If, however, the pockets are full, the gates V V are opened and the surplus coal

dropped into the storage-space beneath, to be shoveled up into the wagons.

The arrangements of double pockets, one on each side of the track, admits of the loading of two sets of wagons at the same time, and as each wagon may be loaded in a few minutes with coal screened and ready for delivery to consumers, the saving of time as well as of manual labor in handling the coal is very great, while the entire space under and on both sides of the track is rendered available for the storage of coal under the best possible conditions.

I claim as my invention—

1. The combination, with an elevated railway-track and its supporting trestle-work, and with inclined coal-pockets M M, formed on each side of the track to extend up to a central point under the same, of openings formed under the track in the crest of the dividing-ridge between the pockets, and gates controlling said openings, whereby the surplus coal delivered from a car after the pockets are filled may, without delaying the car, be passed into the storing-space under the pockets, substantially as and for the purpose herein set forth. 80

2. The combination, with an elevated railway-track, trestle-work supporting the same, inclined coal-pockets M M, formed on each side 95 of the track to extend up to a central point under the same, and openings formed under the track in the flooring between the pockets, of a plate, T, supported immediately under said openings at a distance from the flooring sufficient to permit lateral openings between the outer edges of the plate and said flooring, and gates V V, adapted to control said openings, substantially in the manner and for the purpose herein set forth. 100

3. The combination, with the rods W, actuating the gates V V of a coal-dump, and passing through a receptacle, M, for the coal, of fixed inclosing-tubes W', adapted to protect the rod from weight and friction of the coal surrounding it, substantially as herein set forth. 110

4. The combination, with an elevated inclined coal-pocket M, and with an elevated chute arranged to project therefrom as an extension of its flooring, of a fixed screen, g, 115 adapted to constitute a portion of the bottom of the chute, substantially in the manner and for the purpose herein set forth.

5. The combination, with the chute of an elevated coal-pocket, M, and with the gate controlling said chute, of a lever, h, extending outwardly from the chute, hinged at one end to the side of the pocket, and hinged also to the top of the gate, substantially in the manner and for the purpose herein set forth. 120

6. The within-described coal dumping, storing, and delivery device, consisting of an elevated railway-track, trestle-work for its support, lateral inclined pockets extending from a central point under the track outward on each side thereof, delivery-chutes and screens at the lower edge of each pocket elevated suf- 125

ficiently to allow a wagon to pass under the same, gates and levers controlling said chutes, openings in the flooring of the pockets at their intersection under the track, and gates controlling the same, and a storage-space under the track protected and inclosed by the floor of the lateral pockets, all substantially as and for the purpose herein set forth.

In testimony whereof I have signed my name to this specification in the presence of two subscribing witnesses.

LEVI HETFIELD.
